UNITED STATES PATENT OFFICE.

CHARLES HILL, OF PORTLAND, OREGON.

CLOTHES-HOOK.

SPECIFICATION forming part of Letters Patent No. 484,417, dated August 12, 1890.

Application filed March 19, 1890. Serial No. 344,546. (No model.)

To all whom it may concern:

Be it known that I, CHARLES HILL, a citizen of the United States, residing in the city of Portland, in the county of Multnomah and State of Oregon, have invented an improved Clothes-Hook, of which the following is a specification.

My invention relates to hooks upon which clothes are hung.

It consists, essentially, of a stationary hook and a movable one inverted over it, the movable hook being capable of vertical motion, and a locking device whereby the movable hook is secured, and a check or ticket which acts as a key to release the movable hook, and other details of construction, which will be more fully described hereinafter.

The object of my invention is to provide a clothes-hook so arranged that clothes can be removed therefrom only by the holder of the check corresponding to the hook. I accomplish this object by means of the device illustrated in the accompanying drawings, in which—

Figure 1 is a perspective view of my device, showing the hook closed. Fig. 2 is a side view in section, showing the hook open; Fig. 3, a longitudinal section with the check in position. Fig. 4 is a cross-section through $\alpha\alpha$ with check out. Fig. 5 is a reversed perspective view of check-holder and check in position. Fig. 6 is a detail of check. Fig. 7 is a detail of spring-bolt.

Referring to the accompanying drawings, A is a stationary hook, and a a guide-tube.

B is a movable hook; b, the notched or serrated shank of A; b', notches in b; b², a raising-spring; C, a locking device; c, a grooved plate; c', a shank of the grooved plate; c², the eccentrically-pivoted operating-handle; c³, a coiled spring for moving c; c⁴, the notched spring-bolts; c⁵, a notch in spring-bolts. c⁶ is a spring for forcing out the key D; D, a check-key; E, the securing-lugs, and F a check-slot.

The construction of my device is as follows: The two hooks A and B project forward, the lower and stationary one A bending upward at the front end and the upper and movable hook bent downward to meet the lower hook. At the rear end of the stationary hook a vertical tube is located, in

which the shank of the upper hook slides. About midway of this tube a locking device is placed, suitably arranged to lock the hook in position when closed. This locking device consists of the notched spring-controlled bolts c⁴, which are placed at right angles across the notched shank b and provided with notches c⁵.

The movable spring-controlled plate c is provided, having a groove or recess in its front surface. A plate or check fits this groove in the spring-controlled plate c. The spring-plate c is also provided with a shank, which extends outwardly through the side of the locking device, its end being provided with an eccentrically-pivoted handle c² for operating the spring-controlled plate c. At the end of the recess or groove in the plate c a spring is provided, opposing the key-check D. A coil-spring surrounds and supports the shank of the movable hook. The ends of the hooks where they come together are roughened or corrugated, as shown in Figs. 1 and 2.

The operation of my device is as follows: When the device is not in use, the check-plate or key D is in the groove of the spring-controlled plate c, and by its interposition the plate c forces the spring-bolts c⁴ back till the notches or grooves are presented in the line of the notched shank, so that the notched shank is free to be raised, passing without obstruction through the notches in the spring-bolts. The coil-spring surrounding it, which is in compression when the hooks are together, raises the upper hook, in which position it is ready for use. A garment can now be hung on the lower hook and the upper hook brought down till it engages with the lower hook, and the device is now ready to be locked. This is accomplished by the following operation: The eccentric handle c² is raised, and by its eccentric attachment draws the shank c' and plate c outwardly in opposition to the coil-springs c³, and by making a quarter-turn with the handle the check D in the grooved plate c is presented to the opening F, through which it is forced outwardly by the spring c⁶. The check-plate D can now be withdrawn entirely, and its absence permits of the spring-bolts moving forward and so engaging with the notches in the shank of the upper hook, thereby securing it in position. It can readily be seen that this

check-plate may be of various shapes. The surface where it engages with the spring-bolt may be provided with projections or depressions, and each separate check may be different from any other, so that any one check will serve to release only the particular hook for which it is designed, which may be indicated on it by name and number or any other suitable means.

- 10 To release the garment from the hook, the operation before described is reversed. The operating-handle is turned and raised, so that the groove is presented to the opening F. Into this opening and groove the check is now inserted and the handle returned and depressed. The spring c^3 is now at liberty to force the plate c forward, and by the interposition of the check-key forces back the spring-bolts till their notches are presented in a line 15 with the notched shank, which is thereby released, as before described.

Having now described my invention, what I claim as new, and desire to secure by Letters Patent, is—

- 20 1. The combination, in a clothes-supporting hook, of a hook provided with suitable means for securing it in a fixed position, a sliding bar projecting forward in a line with the hook, so that its outer end is adapted to engage the 25 outer end of the hook and provided at its rear end with a notched shank, and a lock-

ing device consisting of the spring-controlled bolts c^4 , the movable plate c, and the check D, through the interposition of which the spring-bolts c^4 are forced out of engagement with the notched shank by the movable plate c, substantially as described.

2. The combination, in a clothes-supporting hook, of a hook provided with suitable means for securing the hook in a fixed position and 40 having a guiding-tube a at its rear end, a movable bar or hook projecting forward in a line with and adapted to engage at its outer end with the outer end of the fixed hook, both outer ends where they engage being supplied 45 with ribbed or corrugated surfaces, the rear end of the movable bar or hook having a notched shank loosely fitted into the guiding-tube a and having a supporting or raising spring b^2 and a locking device C, consisting 50 of the spring-controlled bolts c^3 , adapted to engage with the notches in the movable shank, a movable grooved plate with its shank and eccentric operating-handle, and the loose plate D, through the interposition of which the spring-bolts are forced back out of engagement with the notched shank, substantially as described.

CHARLES HILL.
